UNITED STATES PATENT OFFICE

WALTER O. SNELLING, OF ALLENTOWN, PENNSYLVANIA, ASSIGNOR TO TROJAN POWDER COMPANY, A CORPORATION OF NEW YORK

BLANK CARTRIDGE

Application filed February 5, 1932. Serial No. 591,023.

My invention relates to improvements in blank cartridges, and more particularly relates to an improved blank cartridge for use in power devices in which the burning of an explosive is utilized to produce mechanical effects other than the propulsion of a bullet or projectile. The principal object of my invention is to provide a blank cartridge which will leave a minimum of residue within the combustion chamber of the power device in which it is employed.

5 In blank cartridges a disc or "wad" of paper, cardboard or like material is utilized at the front end of the cartridge as a retaining means for the charge of powder. When blank cartridges of the present type are utilized for power effects, as in cutting, riveting, splicing or similar mechanical devices, the carbonaceous residue from these 10 discs or wads tends to accumulate within the explosion chamber or piston chamber of the mechanical device, and tends to impair the normal efficiency of the apparatus through small particles of such residue becoming wedged between the sides of the piston and the walls of the explosion chamber, and thus materially increasing friction 15 within the apparatus and notably reducing its efficiency.

20 I have discovered that by employing a disc of an explosive material such as nitrocellulose or a pyroxylin composition as the closure disc in a blank cartridge, I am able not only to increase the explosive efficiency 25 of the blank cartridge, but in addition I can materially decrease the amount of residue accumulating within the explosion chamber.

30 In order to increase the safety of cartridges made in accordance with my present invention from ignition by sparks, I prefer to coat the outer or exposed surface of my explosive disc or wad with a very thin film of a non-explosive material of relatively high heat-conducting capacity, such for example 35 as gold leaf, silver leaf, aluminum foil, or the like.

40 In the drawing forming a part of this specification I have shown, partly in plan and partly in a "cut-away" section, a blank cartridge made in accordance with my pres-

ent invention. In this drawing A is the shell wall of the blank cartridge and B represents grains of the explosive forming the charge. C is the wad of explosive material which I 55 employ as the confining means for the explosive charge in my blank cartridge, and D is the protecting film on the exposed surface of the explosive disc.

50 As a suitable material for the preparation of my explosive disc I prefer to employ a mixture of approximately 50% of nitrocellulose and 50% of nitroglycerin, this mixture forming a horny mass which may be readily formed into thin sheets from which discs of 60 the proper size may be readily cut. Many 65 equivalents for this preferred mixture may be employed, however, and I may employ any suitable explosive mixture of nitrocellulose, nitrostarch, or a nitrosugar with a suitable 70 colloiding agent. As colloiding agents I 75 may employ any of the usual materials such as nitroglycerin or a nitroglycol, acetone, ethyl acetate, camphor, ether-alcohol or the like. I may add to the nitrocellulose forming the base of my explosive wad any of the 80 usual agents employed in the manufacture of nitrocellulose propellant explosives and I prefer to employ a small amount of diphenylamine as a stabilizer, and I may also employ small amounts of any suitable plasticizer such as diethylphthalate, triphenylphosphate or cresolparatoluenesulfonate as a 85 means of insuring the desired consistency of my disc or wad over a long period of time, and the avoidance of such brittleness as might 90 cause the disc or wad to crack and permit the explosive charge to run out of the shell.

95 Instead of employing a disc or wad of a colloided explosive material I may employ a disc or wad of uncolloided nature, as for example a sheet or fabric made up of matted fibers, preferably consolidated by the use of a small amount of a suitable adhesive. In one form of my invention, for example, I employ a disc composed of matted fibers of nitrocellulose and I may employ a partially 100 colloided mass of matted fibers, such as is obtained when a matted mass of nitrocellulose fibers is slightly moistened with a dilute solution of nitroglycerin. In employing

discs of either uncolloided or colloided nature I may employ a solution of nitrocellulose or other suitable adhesive material as a means of attaching or cementing the edge of my disc or wad to the shell walls at the point of contact, and a nitrocellulose solution may also be employed to waterproof the disc or wad where additional resistance to the absorption of moisture is desirable, although with the use of a colloided disc or wad I do not find such additional waterproofing to be necessary.

The protecting coating which I prefer to employ on my explosive disc or wad may be adhesively attached to one side of the disc, or may be held in position by mechanical pressure alone. When employing a protecting coating of aluminum, gold, or silver leaf on the front or exposed surface of my disc I find it desirable to have the coating material firmly attached to the disc, and with pulverulent substances such as bronze powders, zinc oxide, calcium carbonate, or equivalents such as films of paint or varnish, I prefer to employ attachment by the use of an adhesive, but when employing tin foil or lead foil as my protecting agent I do not find that such adhesive or mechanical attachment is at all necessary.

In the firing of my improved blank cartridge, the cartridge is utilized in the power device in exactly the same manner that blank

cartridges are now employed in such apparatus or devices. The burning of the explosive charge in the cartridge brings about the combustion of the improved explosive or combustible wad, and the very high temperature produce disintegrates, atomizes or volatilizes the protecting disc, with the elimination of any considerable amount of unburned carbonaceous residue such as is always left after the firing of blank cartridges of the type now manufactured.

As it will be evident that many equivalents may be employed and many modifications may be made within the scope of the present disclosure, no limitations should be placed upon my invention except such as are indicated in the appended claims.

I claim:

1. A blank cartridge comprising a metallic shell, a charge of explosive within such shell, and a closure wad of an explosive composition one surface of which is coated with a metallic protecting film.
2. A blank cartridge comprising a metallic shell, a charge of explosive within such shell and a closure wad of an explosive composition the outer surface of which is coated with a metallic protecting film.

In testimony whereof, I have hereunto subscribed my name this 3rd day of February 1932.

WALTER O. SNELLING.
